(57) **CLAIM**

The ornamental design for a weight measurement scale, as shown and described.

DESCRIPTION

FIG. 1 is a perspective view from above of a weight measurement scale, showing my new design;

FIG. 2 is a top plan view thereof;

FIG. 3 is a front elevation view thereof;

FIG. 4 is a left side view thereof;

FIG. 5 is a right side view thereof;

FIG. 6 is a rear elevation view thereof; and,

FIG. 7 is a bottom plan view thereof.

The broken lines shown throughout the drawing views are for illustrative purposes only and form no part of the claimed design.
